SOUND ABSORBING STRUCTURE

Theodore M. Prudden, Hingham Center, Mass.,
assignor to Pacific Mills, Lawrence, Mass., a
corporation of Massachusetts

Application June 14, 1933, Serial No. 675,768

18 Claims. (CL 154—44)

This invention relates to a method of absorbing sound and to an acoustic facing for the walls of rooms and other enclosures absorbing sound according to my method. It operates, though in somewhat varying degree, both in preventing sound entering a room, leaving a room, or causing undesirable echoes and reverberations or other results in a room. Thus this method functions both to absorb the sound and to insulate against the transmission of sound through my material. In the claims the term "sound absorbing" covers both these functions.

There are many sound absorbing materials known which absorb sound and are explained in prior patents. My method of sound absorption is, I believe, new. It consists in placing in the path of the sound waves a series of spaced, loosely hung, light, resilient sheets which are set in vibration by the sound waves striking them (which may or may not be individually vibrarily responsive thereto to reproduce the sound) but which in the aggregate change a large part of the sound waves to a form of vibration which is not returned to the room or passed through the acoustic material as audible sound. To apply this method of sound absorption by vibration I have designed an acoustic panel which carries out my method effectively for practical purposes.

In making an acoustic panel for a room some outside covering is desirable which will be attractive in appearance, will permit of decoration and will not interfere unduly with the acoustic results of the remainder of the panel. Moreover, even with the best known methods of treating the inner cloth materials of my panel it is always desirable to add to the fire resistant qualities of the whole panel. An outer coating of a fibrous material properly fireproofed will act like the screen around a miner's safety lamp and appreciably delay the penetration of the flames through the outer coating. Accordingly I have suggested such a facing, which, however, need not be used if the circumstances do not require it and make it undesirable.

The particular panel here shown, though effective, may be varied to a substantial extent according to the requirements of the enclosure in which it is to be used without departing from my method. Special details of construction, which are of advantage in various circumstances, are hereinafter given more in detail in the specification and referred to in the claims.

Fig. 1 is a plan view of a portion of a wall having my improved facing panel thereon.

Fig. 2 is a view similar to Fig. 1 but illustrating a modified method of applying the facing panels.

Fig. 3 is an enlarged sectional detail of a panel taken along line 3—3 of Fig. 1.

Fig. 4 is an enlarged sectional detail of a side edge of the panel also taken along line 3—3 of Fig. 1.

Fig. 5 is a plan view of the panel of Fig. 3.

My invention for convenience is constructed in the form of a panel for application to the wall 12 or other surface that is to be acoustically treated. The panels are conveniently rectangular and each consists of a sound absorbing body section 14 and a cover or facing 16 that is applied to the inner or front face of the body 14 and preferably has its side edges 18 reflexed over the side edges of the body 14 thereby partly to enclose the body and also to form an ornamental boundary for the panel. The cover plate 16 preferably is composed of a stiff porous material as a sheet of cloth, perforated metal, wire screening or felt. This sheet should be chosen to reflect the desired percentage, usually the least possible amount, of the sound waves reaching it, the portion not reflected or absorbed, passing through. A sheet of hard sisal felt is for most rooms satisfactory since it is porous, stiff and self-supporting, transmits sound readily and reflects a moderate amount, about 28%, unchanged from its surface and takes paint readily. The main function of the cover sheet 16 is to shield and hide the sound absorbing section 14 and to provide a surface that can be ornamented. The section 14 is composed of an outer thin sheet 20 which may be a loosely mounted light thin paper preferably of the tissue type, but metal foil or other suitable readily vibrative material may be used. Very little sound is reflected from this sheet. It ordinarily vibrates to the sound waves reaching it and transmits them within the sheet. Whatever the cause of its action, however, I find its use advantageous and its omission harmful. In contact with the paper sheet are two superimposed layers 22 and 24 of thin loosely woven cotton cloth resembling tobacco cloth. Next are two other superimposed layers of similar cloth 26 and 28 that are spaced from the first mentioned cloth layers 22, 24 by three parallel spacers 30, two disposed at the opposite edges of the sections and the third disposed in the middle of the section. The spacers 30 can be of any suitable material as cloth, felt or other material and can be relatively thick as compared with the thickness of the cloth layers 22, 24 and 26, 28. A thickness of $\frac{1}{8}$ inch is quite satisfactory. The width can be anything neces-

20
30
40
50

sary for spacing and attaching purposes and should preferably not be so wide as to overlie a large area of the cloth layers. The spacers are as long as the length of the section 14. Since it is convenient to make the sections about 16 inches square, the spacers will be 16 inches long. The section is further provided with two additional superimposed similar cloth layers 32, 34 separated from the layers 26, 28 by spacers 36 similar to the spacers 30 and a fourth strata of superimposed layers 38, 40 of similar cloth spaced from the layers 32, 34 by spacers 42. A single sheet 44 of cloth is superposed on the multiplicity of sheets 38 and 40 and is spaced therefrom by the spacers 46. A single sheet 48 of thin paper, tissue for instance, is interposed between a single layer 44 and the double layer 38 and 40, and is superimposed upon the layer 40 and is held in place by the middle spacer 46, the sheet having its side edges terminated close to but short of the outside spacers so that the paper sheet is confined only in its middle and the ends are free and unconfined, as is the paper sheet 20. Next to the single sheet 44 is a second single sheet of cloth 50 which is spaced from the sheet 44 by spacers 52. Next is a backing sheet 54 which is spaced from the sheet 50 by spacers 56. The backing sheet preferably is a sound reflecting sheet for which purpose a kraft paper sheet is quite satisfactory. A sheet of polished metal foil can be used as the backing sheet. A single sheet of thin tissue paper 58, crepe for instance, is interposed between the sheets 50 and 54 and is superimposed upon the sheet 50 and is held in such position by the middle spacer 56, the ends of the crepe sheet being terminated close to but short of the end spacers 56 so that the sheet is bound into the section only at its middle. The various layers and spacers together with the cover plate 16 are all bound together in the aforesaid relation by suitable binding means as the binding wires 60 which pass through the superposed layers and spacers. The panels as thus constructed are secured to a wall 12 or other surface by suitable patches 62 of an adhesive that is applied to the wall and to the innermost sheet 54 of the panel or in any other suitable manner that does not interfere with the function of the panel, the panels being arranged with their edges in line as illustrated in Fig. 1, or staggered as in Fig. 2, or in any other suitable arrangement. All the layers of the section and particularly the interior layers are loosely draped between the spacers. Being so hung and being light and resilient they are individually (or in pairs when hung in pairs) vibratory responsive that is, they flap, in response to the sound waves. I have found that on account of this loose hanging and vibratory responsiveness the sound waves received are absorbed. This absorption may be in one or more of several ways. The mere change of the sound waves to a vibratory motion not producing audible sound will itself, of course, destroy the sound wave so changed but also, if a sheet, for instance the first tissue sheet 20, actually vibrates so as to reproduce the sound it receives that wave proceeds to the next sheets and is ultimately damped out by them. The paper sheets are treated in any suitable manner to render them fire-resistant. One of the advantages of crepe paper over a tissue paper is that it can be obtained fireproofed. The fabric sheets and also the spacers are also rendered fireproof or fire-resistant. To this end they can be impregnated with a 25% solution of water glass and then after being dried 75 can be treated with a 10% solution of a fireproof-

ing solution known as Blackstone salts, which probably combines with the water glass and forms a compound that is not harmfully affected by varying humidity conditions. The water glass and also the fireproofing salt treatment imparts a certain amount of stiffness to the cloth which facilitates its assembly into the panel.

A reflected sound wave from an inner part of the panel may be out of phase with a vibrating outer sheet, as for instance, the sheet 20, so that the reflected wave tends to reduce by interference the vibration of the sheet and the sheet to damp the reflected wave. It is difficult to state to what extent this fact may affect the efficiency of the panel as a whole.

The words textile fabric are used in this specification broadly to include felts and paper except where limited by the context.

I claim:

1. A sound absorbent panel construction comprising a multiplicity of slightly spaced loosely-draped light, thin individually vibratile sheets located between stiffer cover and backing sheets, at least the cover sheet being sound permeable, and means uniting all sheets into a unitary structure.

2. A sound absorbent structure comprising a multiplicity of superposed closely-spaced layers of loosely-draped light, thin, vibratile sheets, some of the layers consisting of a plurality of superimposed sheets and other layers consisting of a single sheet the spacing between the vibratile sheets being not materially greater than one-sixteenth of an inch.

3. A sound absorbing panel comprising a multiplicity of slightly-spaced loosely-draped light, thin, vibratile sheets, some being a textile material and some being paper, the paper sheets being in loose contact with confronting textile sheets.

4. A sound absorbing structure comprising a freely vibratile sheet, and a second sheet overlying and bearing lightly and loosely upon said vibratile sheet.

5. A sound absorbing structure including a freely vibratile sheet, a support for peripheral portions thereof, and a second sheet attached to said support and having a free unattached portion overlying and lightly engaging loosely a surface of said vibratile sheet, said two sheets being capable of relative movement therebetween in response to the sound.

6. A sound absorbing structure comprising a series of confronting slightly-spaced light loosely-draped sound absorbing sheets capable of vibrating under influence of the sound, the sheets having confronting free faces and the spacing between the sheets being not materially greater than one-sixteenth of an inch.

7. A sound absorbing structure as in claim 6 there also being sheets that are in loose contact with said first named sheets.

8. A sound absorbing structure as in claim 6, the sheets being in the main composed of material having the nature of tobacco cloth.

9. A sound absorbing structure as in claim 6, the sheets being thin and largely sound-permeable.

10. A sound absorbing structure comprising a series of confronting slightly-spaced light thin sound absorbing sheets capable of vibrating under influence of the sound, and empty spaces between the sheets, the spacing of the sheets being only about sufficient to permit independent vibration of the sheets, a sound reflecting backing sheet confronting and disposed at the end of said

series of sound absorbing sheets and means connecting all sheets into a unitary structure.

11. A sound absorbing structure as in claim 10, some of said sound absorbing sheets characterized by being largely sound-permeable, and other sheets interposed between certain sound absorbing sheets characterized by being largely sound reflecting.

12. A sound absorbing structure comprising a multiplicity of confronting, thin, spaced, loosely-draped, sound-absorbing sheets having free confronting faces and capable of vibrating under influence of the sound, spacers interposed between said sheets at spaced intervals, a thick porous sound penetrable cover which overlies and screens said sheets, and means which secures said sheets and spacers and cover together.

13. A sound absorbing panel comprising a multiplicity of confronting, slightly spaced, loosely-draped, sound-absorbing sheets capable of vibrating under influence of the sound, and connected to each other at widely spaced intervals, the spaces between the sheets being empty and not greatly in excess of that permitting independent vibration of the sheets, and an outer cover of porous sound-permeable material which screens underlying sheets.

14. A sound absorbing structure as in claim 13, said cover having its marginal edge portions reflexed to overlie the edge portions of the underlying sheets.

15. A sound absorbing panel comprising a plurality of superposed spaced loosely-draped, sound-absorbing textile sheets capable of vibrating under influence of the sound, the spaces between said sheets being empty, a sound-reflecting backing sheet, a sound permeable cover sheet, and binding means connecting said sheets at intervals,

and paper sheets interposed between certain confronting textile sheets and engaged lightly with one of the confronting sheets.

16. A sound absorbent structure comprising a plurality of closely-spaced, loosely-draped layers of cloth, a paper backing sheet on one face of the structure, the cloth layers comprising a single thickness of cloth adjacent said backing sheet and a double thickness of cloth adjacent the opposite face, there being a thin loosely-draped paper sheet interposed between two cloth sheets in the middle of the structure and a loosely-draped thin paper sheet between said first paper sheet and said backing sheet.

17. A sound absorbing panel adapted to be applied as a unit to the wall of a room, said panel comprising a multiplicity of light thin loosely draped sound-vibratory sheets, means which connects and retains the sheets in panel-form, said sheets being separated from one another by an amount that is not greatly in excess of that permitting independent vibration of the individual sheets, and vibration controlling means which are located between certain confronting sheets but do not bridge the spaces therebetween and which bear loosely upon one of the confronting sheets.

18. A sound absorbing panel comprising a multiplicity of light thin loosely draped slightly separated sheets, the sheets being separated by an amount that is not greatly in excess of that permitting independent vibration of the individual sheets, and other light thin sheets overlying and in light loose contact with some of said first named sheets and operative to damp the vibrations thereof.

THEODORE M. PRUDDEN.
